(57) **CLAIM**

The ornamental design for an E-cigarette tip, as shown and described.

DESCRIPTION

FIG. 1 is an isometric view of an E-cigarette tip embodying my new design;

FIG. 2 is a front elevation view of FIG. 1, where the back side is identical;

FIG. 3 is a right elevation view of FIG. 1, where the left side is identical;

FIG. 4 is a bottom plan view of FIG. 1;

FIG. 5 is a top plan view of FIG. 1;

FIG. 6 is a perspective view of FIG. 1 shown in an environment of use;

FIG. 7 is an isometric view of a second embodiment of an e-cigarette tip embodying my new design;

FIG. 8 is a front elevation view of FIG. 7, where the back side is identical;

FIG. 9 is a right elevation view of FIG. 7, where the left side is identical;

FIG. 10 is a bottom plan view of FIG. 7;

FIG. 11 is a top plan view of FIG. 7; and,

FIG. 12 is a perspective view of the structure of FIG. 7 shown in an environment of use.

In the drawings, the broken lines are for the purpose of illustrating portions of the e-cigarette tip and form no part of the claimed design.

Furthermore, the additional broken lines shown in FIGS. 6 and 12 are for purposes of illustrating environment that forms no part thereof.

1 Claim, 5 Drawing Sheets
